HATCH COVER CLAMP ACTUATING LEVER

E. C. Knudsen and Henry R. Knudsen,
Superior, Wis.Original application January 31, 1951, Serial No.
208,804. Divided and this application April 23,
1952, Serial No. 283,862

1 Claim. (Cl. 81—3)

1

This invention relates to tools of the type used for securing and releasing clamps and the like, and in particular a one piece wrench having open sockets in the faces of one of the ends of the heads thereof and hook-like sockets extended from the opposite ends of the heads.

This is a divisional application, being divided from copending application filed January 31, 1951, with the Serial No. 208,804.

The purpose of this invention is to facilitate actuating a clamp of a hatch of a ship wherein one wrench is adapted to force a clamp to a locked position when turned to one position and to move the clamp to a released position when turned over.

Because it is essential to retain a hatch cover in sealed relation with a hatch it is desirable to use comparatively tight fitting clamps and in using C-type clamps where an adjusting screw engages the upper surface of the cover of the hatch and a pivotal connection at the opposite end of the clamp passes over the center considerable force is required to move the clamp from one position to another. With this thought in mind this invention contemplates a wrench having a stock with an extended handle and a head wherein with one end of the head anchored on a fixed element of the hatch a pivot pin gripped by the opposite end may readily be moved over the center for securing and releasing the clamp.

The object of this invention is, therefore, to provide means for forming a wrench whereby one end of a head at the end of a stock thereof may be anchored on a fixed element while the opposite end of the head is moved, selectively, to push or pull the pivotal connection of the clamp over the fixed element.

Another object of the invention is to provide a latch or clamp actuating wrench that is adapted to be used on clamps now in use without changing the design or arrangement of the clamps.

A further object of the invention is to provide a clamp releasing and closing wrench which is of a simple and economical construction.

With these and other objects and advantages in view the invention embodies a one piece wrench having a handle extended from a stock with transversely disposed heads on arms on the opposite end of the stock and with the heads provided with recesses in one end and hook-like sockets on the other.

Other features and advantages of the invention will appear from the following description taken in connection with the drawing, wherein:

2

Figure 1 is a side elevational view showing the head end of the wrench illustrating the wrench in the position of releasing a clamp of a hatch wherein the clamp and hatch are shown in dot and dash lines.

Figure 2 is a plan view of the wrench with part of the handle broken away.

Figure 3 is a side elevational view of the wrench also with part of the handle broken away and in which part of the stock is broken away and shown in section to illustrate a nut gripping socket therein.

Referring now to the drawing wherein like reference characters denote corresponding parts the improved hatch cover wrench of this invention includes a stock 10 which is in the form of a yoke having parallel arms 11 and 12 on the ends of which are heads 13 and 14, respectively, and at the opposite end of the stock is a handle 15.

Each of the heads is provided with an open socket 16, in the face of one end, and a socket 17 in the opposite end, the socket 17 being formed with hook-like projections 18.

The stock 10 is provided with nut gripping sockets 19 and 20, the socket 19 having six sides and adapted to grip a hexagonally shaped nut and the socket 20 having four sides so that it is adapted for gripping square nuts.

With the parts formed in this manner a hatch clamp, as indicated by the dot and dash lines 21, pivotally mounted on a lug 22 of a hatch 23 with a link 24 and pins 25 and 26 is actuated to the releasing position with the sockets 16 placed over the pin 25 and with the pin 26 positioned in the socket 17. With the parts in these positions upward movement on the handle 15 draws the pin 26 outwardly over the center of the pin 25 as illustrated in the drawing whereby the clamp is released.

When it is desired to reverse the position of the clamp to secure a hatch cover 27 in sealed relation with a hatch the wrench is turned over with the hooks 18 positioned around the pin 25 whereby the sockets 16 are positioned against the pin 26 and with the wrench in this position the pin 26 may be forced inwardly over the dead center of the pin 25 and bolt 28 whereby the clamp will be actuated to the locked position.

The clamp 21 may be provided with an adjusting screw 29 and this screw may be turned with one of the sockets 19 or 20 placed over the head thereof, thereby making it possible to use the wrench for adjusting the clamp and also for actuating the clamp to open and locked positions.

Although the clamp is designed for use in opening and closing hatch clamps it will be understood that it is also adapted for use on different types of machinery and equipment.

It will be understood that modifications within the scope of the appended claim may be made in the design and arrangement of the parts without departing from the spirit of the invention.

What is claimed is:

A hatch clamp wrench comprising a stock 10 including spaced parallel arms extending from one end with a handle extended from the opposite end and said arms having heads transversely positioned thereon, said heads having open sockets in the outer faces and positioned in one of 15

the ends thereof, and hook-like projections providing sockets in the opposite ends, said sockets being arranged on opposite faces of the heads and being arranged in opposed relation to each other.
